CONTROL CONSOLE FOR AN INFORMATION RETRIEVAL SYSTEM

John Libero Gianfagna, Staten Island, N.Y., assignor to
Sperry Rand Corporation, New York, N.Y., a corpora-
tion of Delaware

Filed Mar. 30, 1967, Ser. No. 6,450

Term of patent 14 years

(Cl. D26—5)

FIG. 1.

FIG. 2.

FIG. 3.

FIG. 4.

FIG. 1 is a front perspective view of a control console for an information retrieval system showing my new design;

FIG. 2 is a rear elevational view thereof;

FIG. 3 is an elevational view taken from the right side thereof; and

FIG. 4 is an elevational view taken from the left side thereof.

I claim:

The ornamental design for a control console for an information retrieval system, substantially as shown.
